FLORENT HINNEKENS, OF PATERSON, NEW JERSEY, ASSIGNOR TO VAN VLAANDEREN MACHINE COMPANY, OF PATERSON, NEW JERSEY, A CORPORATION OF NEW JERSEY

APPARATUS FOR TREATING FABRICS

Application filed May 2, 1927. Serial No. 188,165.

The object of this invention is to provide a machine for washing or otherwise treating piece goods and especially fabrics of considerable length, as in the processes incident or 5 preliminary to dyeing. The invention contemplates the provision of a support and a perforated sleeve journaled on the support with its axis substantially horizontal and projecting laterally from the support above the 10 base thereof and with its outer end free, the support having means to deliver liquid to the sleeve and the sleeve having its outer end closed against liquid delivery; the goods, in the form of a roll or bolt, is placed on or 15 looped over the sleeve so that its plies or convolutions surround the same and all are transversely distended, or flat, and when the sleeve is rotated and the liquid caused to flow into the same under proper pressure the treatment 20 is performed in a very thorough and expeditious manner, especially as according to the best procedure the roll of goods is of so much greater diameter than the sleeve that is loosely hangs therefrom, which, in view of the 25 manipulation which thereby naturally results as it rotates with the sleeve, is a factor in thoroughly impregnating the goods and (in washing) in insuring the removal of all foreign substances therefrom. In the best form 30 there is provided means, as a baffle, for preventing escape of the liquid from the sleeve in the downward direction. This has in view to concentrate the liquid jets while conserving the liquid. Preferably the perforations 35 in the sleeve are so formed that those for each half of its length are inclined from the interior to the exterior surface of the cylinder toward its adjacent end, whereby the jets delivered thereby will be in two diverging sets, and 40 this will act to distend the goods laterally or keep it so distended. Usually for the sake of conserving the liquid there will be a vat under the sleeve in which the falling liquid is received and from this the means to deliver liquid into 45 the sleeve takes its supply. I keep the depending part of the fabric preferably above the liquid level so that it does not become contaminated by any scum or other refuse on or in the liquid.

50 In the accompanying drawing,

Fig. 1 shows the apparatus in side elevation, partly in section;

Fig. 2 is a right-hand end elevation, partly broken away;

Fig. 3 is a section of the end portion of the 55 spray sleeve, the liquid supply pipe and the baffle; and

Figs. 4 and 5 are sections on lines 4—4 and 5—5, respectively, Fig. 3.

An upright frame is shown at 1. To one 60 side of this frame is a long vat or tank 2 from which leads a pipe 3 containing a pump 4 and extending from the pump first upwardly alongside the frame and then horizontally over the frame, on which it is supported, its 65 free end projecting beyond the frame and over the vat. The projecting portion of the pipe is provided with holes 5 open only upwardly. The free end of the pipe is closed and has a trunnion 6. 70

At its free end and on its projecting portion more or less close to the frame 1 the pipe has two squared or otherwise polygonal enlargements 7 and on these are fitted the upstanding collars 8^a, conforming thereto, of a soft rubber baffle or dam 8 which is arranged beneath 75 said portion of the pipe and presents a convex underneath surface conforming to a cylinder: see Figs. 4 and 5, from the former of which it will appear that for practically its whole 80 length and excepting where the collars exist this baffle is preferably concavo-convex, so that it is somewhat limber.

Fitted over the projecting portion of the pipe is the spray sleeve. This is a perforated 85 cylinder 9 preferably having flanges 9^a after the manner of a reel. Its outer end is closed by a cap 10 screwed thereon. Its inner end is screwed onto the projecting collar 11^a of a head here comprising a worm-wheel 11, the 90 receiving member 12 (to which the worm-wheel may be suitably fixed in any way) of a gland and the entering member 13 of such gland secured to the receiving member by screws 14, 15 being the gland packing. By 95 means of this head and a bearing 10^a in the cap 10 which receives the trunnion 6 the spray sleeve is journaled on the pipe, being kept from displacement toward the free end of the pipe by the obstruction (to the head) which 100

the inner enlargement 7 and rubber collar 8^a afford and by the engagement with the worm-wheel of the hereinafter mentioned worm. The head being already assembled with the pipe the baffle is fitted thereto and finally the spray sleeve, with its cap in position, is fitted over the pipe and baffle and its inner end screwed onto the collar 11^a of the head. The projecting portion of the pipe serves not only to supply the liquid but as a simple means to support the sleeve and the baffle.

The means to rotate the spray sleeve is here shown as comprising a worm 16 in mesh with the worm-wheel and journaled in the frame and having a pulley 17, an endless chain embracing this pulley, and another pulley 18; any prime mover, as a motor, may be used to drive the shaft 19 for the latter pulley.

The operation and preferred manner of treatment are as follows: Having first filled 20 the vat and wound up the goods, flat, in a roll which exceeds in diameter the spray sleeve, so that the goods will hang free from the sleeve when arranged thereon as shown in Fig. 2 but 25 will not depend thereinto, the pump is operated and the spray sleeve rotated. The goods now undergo spraying, the pumped liquid being forced through the holes in the pipe and then from the sleeve in the form of jets. The 30 liquid is thus made to pass always in one direction, or outward through the goods, so that the goods is thoroughly impregnated and all foreign matter is carried away and falls into the vat. The force of this spray 35 is concentrated because of the baffle 8, which by hugging closely the sleeve prevents issue of the liquid downward through those holes of the sleeve which happen to be underneath. Without this baffle a large part of the spray 40 would issue (downward) to no purpose and it would require extra effort on the part of the pump to give sufficient force to the spray where it is serving a useful purpose (i. e., where the goods tends to hug the sleeve at its 45 upper half) to make it effective. Of course the liquid is used until it is exhausted, by which I mean in the case where washing is being done, until it is so far contaminated as to need replenishing; but by keeping the 50 goods above the liquid level any scum or other refuse which collects on the surface is prevented from accumulating on the goods.

The perforations of the sleeve, as indicated at 9^b in Figs. 1 and 3, are formed so that those 55 of each end portion, here one-half of the length of the sleeve, diverge with respect to an intermediate plane perpendicular to the axis of the sleeve. Thus the jets of spray as to the two end portions of the sleeve 60 diverge and this has a very helpful effect in keeping the goods distended and free from folds or wrinkles.

Having thus fully described my invention, what I claim is:

1. In combination, a support having a liq-

uid non-revoluble delivery pipe projecting laterally and rigidly therefrom and a perforated revoluble sleeve penetrated by and journaled on the pipe with its outer end free, said pipe affording support for both end portions 70 of the sleeve and having restricted means to deliver liquid into the sleeve at different points throughout substantially the whole length of the latter and said sleeve having its outer end closed against liquid delivery and being adapted to have the roll of goods to be treated looped over the same from its said outer end.

2. In combination, a support, a perforated sleeve journaled, with its axis substantially horizontal, on and projecting laterally from the support above the base thereof, said support having means to deliver liquid to the sleeve and said sleeve having its outer end closed against liquid delivery, and a non-revoluble baffle carried by the support and arranged to obstruct downward flow of liquid from the sleeve through the perforations thereof. 80

3. In combination, a support, a perforated sleeve journaled, with its axis substantially horizontal, on and projecting laterally from the support above the base thereof, said support having means to deliver liquid to the sleeve and said sleeve having its outer end 90 closed against liquid delivery, and a yielding non-revoluble baffle carried by the support within and close to the sleeve and arranged to obstruct downward flow of liquid from the sleeve through the perforations thereof. 95

4. In combination, a support, a perforated sleeve journaled, with its axis substantially horizontal, on and projecting laterally from the support above the base thereof, said support having means to deliver liquid to the sleeve and said sleeve having its outer end closed against liquid delivery, said sleeve having its perforations at each end portion thereof divergent with respect to an intermediate plane perpendicular to the axis of the 100 sleeve. 110

In testimony whereof I affix my signature.

FLORENT HINNEKENS.
